UNITED STATES PATENT OFFICE.

THEODORE A. STEINMETZ, OF EAU CLAIRE, WISCONSIN, ASSIGNOR OF ONE-HALF TO
ARTHUR L. PAYNE, OF EAU CLAIRE, WISCONSIN.

AUTOMATIC DUPLICATING-MACHINE.

1,401,826.

Specification of Letters Patent. Patented Dec. 27, 1921.

Application filed September 11, 1920. Serial No. 409,734.

To all whom it may concern:

Be it known that I, THEODORE A. STEINMETZ, a citizen of the United States, and resident of Eau Claire, in the county of Eau Claire and State of Wisconsin, have invented a new and Improved Automatic Duplicating-Machine, of which the following is a full, clear, and exact description.

It is well appreciated that numerous duplicating machines have been placed upon the market. These devices usually included a tracing arm with which an arm, supporting a cutter member is associated. Both of these arms are either capable of movement one in proportion to the other, or a tracing of the work to be cut is moved under these arms in such a manner that the tracing or pattern lies under the tracing arm, and the work to be cut underlying the cutter arm, so that the work is operated upon in the manner desired.

These machines, aside from the operation of the cutting wheel, are operated manually, it being incumbent upon the operator to move the tracing arm over the pattern, or tracing, or in the instance of the other machine being used, to move the pattern under the tracing arm.

Aside from this difficulty, cutting machines heretofore constructed have with difficulty, duplicated the work to be cut, the details such as depressions, etc., of the pattern.

This difficulty is to be attributed to the uncertainty of manual operation, in that an operator may bear more heavily upon the tracing arm over a certain depression than over others, thus causing the variance described.

It will also be understood, that aside from depressions, etc., that a variation is liable to occur in connection with the side edges of a pattern due to the same defect heretofore enumerated.

With this defect in mind, I have constructed a machine in which duplication will be effected, which duplication may be relied upon to be an accurate reproduction of the pattern.

A further object of my invention is the construction of a machine of this type which shall be entirely automatic in operation, aside from starting and stopping the same,

so that the defects incident to the human equation are eliminated.

A still further object of my invention is the construction of a device of the type specified, which shall be entirely simple in the arrangement of its parts and in operation, so that no difficulties due to a complication of mechanical movements may be experienced.

Reference is had to the attached sheets of drawings as illustrating one practical embodiment of my invention, and in which,

Figure 1 is an enlarged partly sectional side view of an automatic duplicating machine constructed in accordance with my invention.

Fig. 2 is a sectional front view taken along the line 2—2 of Fig. 1.

Fig. 3 is a plane view of the machine, and Fig. 4 is an enlarged partly sectional side view of a certain detail of construction.

In these views the reference numeral 5 indicates legs of any suitable character, which support the base 6, it being noted that a further supporting bar 7 is provided, which supporting bar conveniently extends between horizontal braces 8.

Journal boxes 9 are secured to one of the legs 5, and supporting bar 7, so as to provide a mounting for shafts 10 which extend therebetween. The base 6 is conveniently formed adjacent one of its ends with an upwardly extending portion 11 which mounts between its upper ends, a shaft 12.

A source of power drives the belt 13, which in turn serves to rotate the pulley 14 mounted upon the shaft 12, this in turn transmitting energy to the pulley 15 serving to drive the belt 16.

A pair of arms 17 are now conveniently provided, which arms rockingly engage the shaft 12, at one of their ends, and are conveniently connected together as at 18 adjacent their opposite ends, and serve to support, adjacent these latter ends, a tracing wheel 19 of any desirable construction, and a cutter or other desirable member 20, which latter is secured to a shaft 21 mounting a pulley 22 over which the belt 16 passes.

A further pulley 23 is also driven by the operation of the belt 13, and a belt 24 passing around this pulley serves to transmit power to a second pulley 25 as in Figs.

1 and 3. This latter pulley is in turn mounted upon the shaft 10 and turns the latter, together with a gear 26, which, by virtue of the fact that it co-operates with the gear 5 wheel 27, serves to rotate this latter member.

A pitman 28 has one of its ends rockingly secured as at 29 to the gear wheel 27, its opposite end engaging the crank 30 of a sector gear 31, rockingly secured to the 10 base 6, as has been indicated by the reference numeral 32.

The base 6 is conveniently formed with dove-tailed recesses in which a table 33 is slidably mounted, such table being formed 15 with a deck 34 which, by virtue of the dove-tailed recesses formed in the table 33 and illustrated in Fig. 1, is slidably mounted upon the table, and in a direction transverse to the motion permitted on the part of the 20 table 33.

In this connection, it is to be noted that the deck 34 is moved and retained in its proper position by virtue of a traveler, comprising an extension 35 formed with a 25 screw threaded opening through which a screw threaded bar 36 extends, the latter being rotatably mounted by having its ends project through openings in the table 33.

It is now to be noted that by virtue of 30 the sector gear 31 engaging the rack 37, which latter forms a part of the table 33, that a rotary motion of the gear wheel 27 is translated into a reciprocating motion on the part of the table, it being further appreciated that by virtue of the relative sizes 35 of the pulleys, 14, 15 and 22, and the reduction gearing composed of the gear 26 and gear wheel 27, that the drive transmitted by virtue of the belt 13 will result in a 40 rapid rotary motion on the part of the cutter 20, and a relatively slow reciprocating motion on the part of the table 33 and the deck 34 carried thereby.

To now provide means whereby the deck 45 34 of the table 33 will be shifted transversely with respect to the table, and at the same time automatically, attention is invited to the construction shown in Figs. 1 and 2 in which it will be seen that that 50 end of the screw threaded rod 36 projecting beyond the table 33 mounts a ratchet 38 engaged by spring pressed pawls 39, which latter are rockingly secured to stops 41 which may be longitudinally adjusted with 55 respect to the base 6. These stops lie in the line of travel of the ratchet 38, and slightly beyond the limit of travel of the same.

It will be obvious that upon the table 33 reciprocating in the manner aforescribed, 60 that the ratchet 38 will be engaged by the lower-and-upper most pawls carried by the opposite stop 41, so that a rotation is imparted to the bar 36 upon the table 37 reaching the limit of its travel in either

direction, which will in turn cause the deck 65 34 of the table to be moved transverse to the path of travel of the table 33 upon the latter being reciprocated. Upon the opposite pawls 39 of the stops 41 being swung 70 to operative position, the other pawls having been moved to a position at which they will not contact with the ratchet 38, it will be obvious that the direction of turning of the bar 36 will be reversed, whereby to retract the deck of the table if this should be 75 desired.

By this construction, it will be appreciated that a pattern such as has been indicated in dotted lines in Fig. 1 and a piece of work may be secured to the deck 34 of 80 the table, and the machine set in operation. The tracing wheel 9 will be raised upon the edge of the pattern moving thereunder, and will subsequently follow any depressions, etc., in the face of the pattern, and 85 will again be lowered upon the rear edge of the pattern moving beyond the tracing wheel 19.

This, as will be appreciated, will cause the cutter 20 to move correspondingly, and it 90 will be understood that a perfect reproduction of the pattern will be made by means of this latter element, for the reason that the table, aside from its reciprocating action, has its deck moving transversely 95 upon it, thus permitting the tracing wheel to move over every part of the pattern to be cut.

Finally it will be understood that it might be desirable to provide a certain medium 100 whereby the tracing wheel might be supported out of contact of the deck 34 with the table 33, and with this in view, the connecting portion 18 extending between the arms 17 has conveniently associated with 105 it, a set screw 44 capable of being operated by means of a knurled head 45.

It will be obvious that this screw which passes through the connecting portion 18 and engages the same may be adjusted longitudinally so as to provide the result desired.

Also it will be seen, reference being invited to Figs. 1 and 4, that the rear edge of the deck 34 is provided with a series of 115 openings 46 any of which may receive pins 47. Further, a lever 48 is associated with the machine, which lever, upon being rocked, serves to operate a crank arm 50, in turn connected to a rod 51, which latter may be 120 coupled with a circuit breaker (not shown). From the foregoing it will be seen that by arranging the pins 47 within the proper openings 46 that these pins may be caused to operate the circuit breaker, thus resulting 125 in the stoppage of the entire apparatus.

Thus I have constructed a cutting machine which shall be entirely simple in construc-

tion, and capable of duplicating a pattern automatically.

Obviously numerous modifications of structure might readily be resorted to without departing from the spirit of my invention, which I claim is:

1. An automatic duplicating machine, including a base, a table slidable within said base, a rack secured to said table, a sector gear engaging said rack, means for rocking said sector gear whereby to reciprocate said table, a deck secured to said table, a screw threaded rod rotatably mounted upon said table, means providing engagement between the deck of said table and said rod, a pair of stops secured to said base, a ratchet carried by said rod, a pawl carried by each of said stops and adapted to engage said ratchet when said table is reciprocated, whereby said

20 rod will be rotated to move the deck of the

table, and a cutter and tracing member adapted to overlie said deck.

2. An automatic duplicating machine, including a base, a table slidable within said base, a rack secured to said table, a sector gear engaging said rack, means for rocking said sector gear whereby to reciprocate said table, a deck secured to said table, a screw threaded rod rotatably mounted upon said table, means providing engagement between the deck of said table and said rod, a pair of stops adjustably secured to said base, a ratchet carried by said rod, a pawl carried by each of said stops, each of said pawls being adapted to engage said ratchet when the table is reciprocated, whereby said rod will be rotated to move the deck of the table, and a cutter and tracing member adapted to overlie said deck.

THEODORE A. STEINMETZ.
